UNITED STATES PATENT OFFICE.

CARL A. PALMGREN, OF CHICAGO, ILLINOIS.

ELECTRIC SWITCH.

1,173,460.

Specification of Letters Patent. Patented Feb. 29, 1916.

Application filed July 2, 1915. Serial No. 37,643.

To all whom it may concern:

Be it known that I, CARL A. PALMGREN, a citizen of the United States, residing at Chicago, in the county of Cook and State 5 of Illinois, have invented certain new and useful Improvements in Electric Switches, of which the following is a specification.

My invention relates to electrical switches and has particular reference to a novel 10 switch for use in connection with registering pyrometers.

In steel plants and other manufacturing establishments in which metals are heat treated, it is common to employ recording 15 pyrometers, *i. e.*, pyrometers located in the heating furnaces and to electrically connect these pyrometers with a recording device which may be located at a distance, as, for instance, in the office of the superin- 20 tendent. To avoid a multiplication of recording devices and at the same time to provide means for recording the temperature of the furnaces at necessary intervals, I have conceived the idea of providing a 25 single pyrometer recorder and connecting said recorder with a plurality of furnaces, interposing in the connection a mechanism which shall automatically make the circuit with the different furnaces alternately, 30 whereby the temperature of each furnace may be recorded for a portion of the time during each hour. For instance, assuming four furnaces connected to a single recording device, each furnace would be connected 35 with the recording device for fifteen minutes during the hour. The number of furnaces may be increased or diminished, as desired, it being certain, however, that irrespective of the number of furnaces, the temperature 40 of each furnace will be recorded for a period of time during each hour, the length of time over which record is made depending upon the number of furnaces in action. This result is secured by connecting the 45 switching mechanism, to a clock-driven shaft, the speed of rotation of which corresponds to that of the minute-hand of the clock. If desired, of course, the shaft might be made to revolve one or more times faster, 50 in which case a record might be made of each furnace at shorter intervals, such record, of course, being of shorter duration than in the case mentioned.

The invention will be more readily understood by reference to the accompanying drawings, wherein—

Figure 1 is a sectional view through a switch constructed in accordance with my invention; Fig. 2 is a sectional view through the casing showing the switch mechanism in 60 elevation; Fig. 3 is an enlarged plan view of the pivoted contact pieces; Fig. 4 is a sectional view through a slightly modified construction; Fig. 5 is a fragmentary plan view of the construction shown in Fig. 4; 65 Fig. 6 is a section through one of the mercury troughs of Fig. 4; Fig. 7 is an enlarged sectional detail of one of the cam-operated parts of the mechanism; Fig. 8 is a detailed elevation of a still further modification; 70 Fig. 9 is an elevation of the construction shown in Fig. 8, and Fig. 10 is a front view of a clock showing the divisions on the face thereof according to the number of furnaces served by the device. 75

Referring more particularly to Figs. 1, 2 and 3, it will be seen that my device is intended to be associated with a clock 10, a shaft 11 of which is operated at a speed substantially equal to that of the minute-hand of the clock. This is according to the present showing of the device, but the speed of this shaft might be varied to suit different conditions as heretofore referred to. The shaft 11 is mounted in bearings in a frame 12 and carries a plurality of cams 13, 14, 15 and 16, which cams are spaced longitudinally on the shaft and located at 90° from each other. The present device is shown as connected to and serving four furnaces, 90 these furnaces being indicated, for convenience, as 17, 18, 19 and 20, as shown in Fig. 10, the intention being that the temperature of each of the four furnaces shall be recorded for a period of fifteen minutes. The mechanism by which the desired result is secured may consist of a recording pyrometer of any approved form and which is not here shown, suitable electrical connections between the pyrometer, the switch of this invention and the furnaces. In the construction of Figs. 1 to 3 the switch mechanism is shown as comprising a shaft 21 pivoted in the frame member 12 and carrying a plurality of bearings 22 of insulating material, to which metallic arms 23 are secured. Two arms constitute a unit, it being intended to illustrate four units, one of which is connected to each furnace. A pair of arms 23 are united at their rear ends, as best shown in Fig. 7, by means of the U-shaped part 24, the legs of which may be formed of insulating

material. The head 25 of the member is adapted to contact with one of the cams 13 to 16 inclusive. Spring members 26 bear upon the arms 23 and tend to force the member 24 in a downward direction. At the forward terminal of the arms 23, I provide screw contact pieces 27, 28, which are adapted to bear upon contact plates 29, 30, which plates are pivoted to the brackets 31 and urged into elevated position by means of the springs 32, connected to short levers 33 on the ends of the contact plates. An electrical connection 34, 35 is provided for each of the contact plates 29, 30, these connections extending to the recording pyrometer (not shown). Electrical connections 36, 37 extend to the heat measuring instrument located in the furnace served by that unit. In Figs. 4 and 6 the connections to the pyrometer and furnace are shown more fully. As will be noted in that figure, I have provided terminals for electrical connections with four furnaces, indicating the number of the furnace in a circle above each of the pairs of terminals.

In the modified construction shown in Figs. 4, 5 and 6 all the parts remain the same except in that the contact plates shown in Fig. 3 are eliminated and in place thereof I have substituted troughs 38, 39, adapted to be filled with mercury, and into which the lower ends of the screw contact pieces are adapted to project.

In the construction of Figs. 8 and 9 I have shown a still further modification of the contact pieces. In that construction the wires leading to the pyrometer terminate in plates 40, 41, having a plurality of spring contact pieces 42, 43 thereon with which the screw contacts may engage.

An advantage in the construction shown in Figs. 1 to 3 is in that no time is lost within which the temperature of no furnace is being recorded, for the reason that as the contact pieces of one unit are being elevated the contact plates 29, 30 will follow the pieces until they engage the descending screw contacts of the next unit. In that way no time is lost.

As explained, the number of furnaces controlled or acting upon the recording pyrometer is not limited, as the shaft 11 may be

provided with any desired number of cams. In case a larger number of furnaces is served, the length of time in which the record is made will be lessened, although it would be entirely practical to increase the speed of the shaft 11 and make a record of each furnace a number of times during each hour, such a record being made for a shorter interval of time. Obviously also other modifications may be made in the construction than those herein shown, and such modifications as are within the scope of my claim I consider within the spirit of my invention.

I claim:

1. In a device of the class described, the combination of a plurality of pairs of pivoted contact pieces, each pair of which is adapted to be connected to a heat measuring device, a single pair of pivoted contact pieces adapted to be connected to a recording device, and means for moving said first-mentioned pairs of contact pieces into engagement with said second contact pieces, said means including a time-controlled shaft and spaced cams on said shaft so arranged as to bring said pairs of contact pieces into action in sequence, substantially as described.

2. In a device of the class described, the combination of a plurality of pairs of pivoted contact pieces, each pair of which is adapted to be connected to a heat measuring device, a single pair of pivoted contact pieces adapted to be connected to a recording device, a time-controlled shaft adapted for one complete rotation during each hour, a cam on said shaft for each of said plurality of pairs of contact pieces, the total effective area of said cams being 360°, said cams being spaced on said shaft and angularly spaced, whereby each of said plurality of pairs of contact pieces is actuated once during each hour, the length of actuation being controlled by the number of these measuring devices which are served, substantially as described.

Signed at Chicago, Illinois, this 25th day of June, 1915.

CARL A. PALMGREN.
